GAS PRODUCER

Heinrich Koppers, Essen, Germany, assignor, by
mesne assignments, to Koppers Company, Pittsburgh, Pa., a corporation of Delaware

Application June 10, 1936, Serial No. 84,397
In Germany June 7, 1935

1 Claim. (Cl. 48—68)

The present invention relates to gas producers, especially to those for the gasification of bituminous fuels, and furthermore the invention relates to improvements useful in pipe steam boilers and 5 similar apparatus.

An object of my invention consists in providing those improvements in gas producers by which the accessibility of the gas producer shaft and an effective control of the gas streams in the gas 10 producer shaft is also provided for, even if the gas producer is provided with an extension at the top in which the bituminous fuel before entering the gas producer shaft is subjected to a heat treatment, for instance for the purpose of distillation.

In order to avoid the adherence of the slag to the walls of the gas producer during the gasification process of the fuel, the gas producer shaft is often equipped with water-cooling jackets. The gas producer shaft then acts like 20 a steam boiler. The resulting steam together with the air blast can be advantageously introduced into the fuel of the gas producer. It is known to equip the gas producer shell similarly to a pipe steam boiler. In this case, the gas producer shell consists of an upper and a lower ring-chamber, which are interconnected by 25 essentially vertical tubes. The slots between these tubes are suitably closed. An especially preferable construction of the means for closing or sealing the slots between the tubes is a further 30 object of my present invention which will be explained in particular in the following:

If above the gas producer shaft itself, in which 35 the fuel is gasified, a special top extension is provided for, in which the fuel is treated with heat, before the gasification for instance for the purpose of distillation or low-temperature carbonization, it is necessary to reduce the section of 40 said top as against the sectional area of the gas producer shaft, as otherwise it will not be possible to reach the grate of the gas producer shaft from above with rods or another suitable poker. The shell of the gas producer therefore has between 45 the gasification chamber and the low-temperature carbonization or distillation chamber a step wherein are provided closable poking holes.

In known gas producers with a step-like low-temperature carbonization chamber the space 50 underneath the step between the gasification chamber and the distillation chamber is often not completely filled-up with fuel. The remaining free space is troublesome to a great extent for the distribution of gases in the gas producer.

55 The gases developed in the lower part of the gasification chamber tend to collect in the free space underneath the step of the shell. With such stepwise construction, the gases will no longer flow upwards in uniformly distributed 60 condition over the whole section of the low-tem-

perature carbonization chamber, but they pass mainly along the walls of the low-temperature carbonization top extension. A proper heat-treatment for instance a uniform low-temperature carbonization of the fuel is thus made impossible.

More or less larger proportions of the fuel, which do not come into contact with the escaping gases, which pass up alongside the walls of the gas producer, will reach the lower part of the 10 gas producer undistilled, whereby the gasification reactions are interfered with.

According to my present invention, these difficulties of the hitherto known gas producers with low-temperature carbonization chambers are in 15 principle eliminated by constructing the conjunction between the low-temperature carbonization and the gasification chamber at an inclination corresponding to the natural gradient of the fuel, so that the fuel charged into the gas 20 producer completely fills up the interior of the gas producer shaft and no hollow spaces can be formed in the fuel column which could be troublesome for the uniform distribution of the gases through the fuel bed. If this basic idea of my 25 present invention is applied to gas producers, which are provided with a shell having the water cooling-jacket in the form of a pipe steam boiler, as I have described it above, then the upper ring-shaped water-chamber is advantageously 30 constructed of a larger diameter than the lower one, so that the shell of the gas producer widens conically from the bottom to the top of the gasification chamber.

Another important object of my invention 35 comprises improvements in the connections between the individual tubes of the gas producer shell.

The manufacture of dense tube walls for heating shells for steam boilers, or shaft shells for 40 gas producers, or for the linings of reaction chambers, in which exists a high-temperature, by closing the slots between the individual tubes by means of straight or bent metallic strips, which are fastened longitudinally to two adjacent tubes 45 is a well-known method.

In such instances, however, the connecting strips are essentially disposed in the connecting line between the centers of two adjacent tubes. This is disadvantageous, since with such construction the tubes must have a rather considerable distance from one another.

A further disadvantage is, that the connecting strips mostly are not subjected to the cooling effect by the cooling medium in the tubes which 55 is especially disadvantageous if the connecting strips are subjected to heat on both sides. Furthermore, it has been suggested to interconnect the tubes at the longitudinal sides by welding, or to insert between the individual tubes metallic 60

filling pieces. The connection of the tubes by welding is however very objectionable, as this connection is not elastic and should the tubes expand, it can easily crack. The heating wall 5 between the tubes formed by the insertion of filling pieces will become quickly leaking, especially if the tubes are exposed frequently to temperature changes.

According to my present invention, for the 10 elimination of the above difficulties, I connect the adjacent tubes of the pipe steam boilers, gas producers or the like, by means of metallic connecting strips, which run essentially transversally to the connecting line between the centers of 15 two adjacent tubes, and connect these strips to the tubes by welding. The strips are welded according to my invention in such a way, that they are fastened with their longitudinal edges each to one of two adjacent tubes. The connection 20 between the tubes will thus be in its section for instance the shape of a Z or the like.

Furthermore, my invention also relates to a new 25 and very advantageous form of the connection between the individual tubes of those gas producers or the like, in which the chamber formed by the tubes enlarges towards the top, so that the spaces between adjacent tubes are small at the one end of the tubes and gradually become larger towards the other end of tubes. According 30 to my invention, the space between the tubes is in this instance closed by a metallic longitudinal strip, which by welding at the longitudinal edges is closely connected with the adjacent tubes and the wedge-like space between the connecting strip 35 and the tubes towards the fire side is filled with suitable refractory stamped mass.

Further objects of my present invention may be taken from the following description of various preferred modes of carrying out my invention.

Fig. 1 of the drawings is a vertical section 40 through a gas producer designed according to my invention.

Fig. 2 is a horizontal section through a part 45 of the gas producer on line II-II of Fig. 1.

Figs. 3 and 4 show on an enlarged scale two 45 methods of carrying out the connection between two tubes.

Figs. 5 and 6 show other modification of the 50 tube connection.

The gas producer as shown in Fig. 1 is provided below with a gasification chamber 1 and above with a distillation chamber 2. The chamber 2 is formed by refractory brickwork 3 which is laid in a shell 4 consisting of iron plates or another suitable material. In the ceiling 5 of the distillation chamber 2 there is arranged a charging-hopper 6, projecting into the inside of the shaft. The fuel to be treated is charged 60 through an opening, which can be closed by a cover 7, into a container 8. The conical bottom 9 of the container 8 is fitted with an opening which can be closed by means of a cone 10. The closure 10 is carried by a chain 11, which is fastened to a lever 12. The shaft 13 passes through the walls of the container 8 in a gas-tight way. A hand lever 14 is fastened outside the container 8 to the shaft 13, which lever carries the weight 15. The weight 15 is so equipped, that the closure 8 even if container 10 is charged, can be kept in its closing position. By pushing the hand lever 14, the closure 10 can be lowered so that the fuel in the container 8 slides into the charging hopper 6. Since the closure 10 can be 75 opened, even when the cover 7 of the container

8 is closed, it is possible to discharge the fuel from the container 8 into the charging hopper 6, without gases escaping through the charging device.

The gas discharge tube 16 is connected to the 5 part of the distillation chamber 2, not filled with fuel, laterally of the charging hopper 6.

As illustrated in Fig. 1, the distillation chamber 2 has essentially the form of a cylinder. The lower gasification chamber 1 is enlarged 10 relative to the distillation chamber 2. The conjunction is formed by an inclined area 17. Openings 19 are arranged in the brickwork 17, which can be closed-up by the plugs 18, for introducing poking rods into the gasification chamber 1 15 through the openings 19.

The gasification chamber 1 is built-up by a number of metallic tubes 20, which are connected above to a ring-shaped water-chamber 21, and below to a ring-shaped water-chamber 22 in a wa- 20 ter-tight way. The chambers 21 and 22 are therefore interconnected by the tubes 20. The tubes 20 are surrounded outside by a shell 23, made of iron-plate or another suitable material. A number of supports 24 are fixed to the shell 23 by 25 means of which the gas producer is supported upon the foundation 25.

As may be seen from the drawings, the upper water-chamber 21 is of a larger diameter than the lower water chamber 22 so that the gasifica- 30 tion chamber 1 enlarges conically from the bottom to the top.

The cooler water pipeline 26 is connected with the lower water-chamber 22, and the hot-water return pipeline 27 is connected to the upper 35 water chamber 21. Both pipelines lead into an evaporator 28, which is situated above the water chamber 21 upon the service platform 29. Due to the elevated position of the evaporator 28, steam is essentially generated, only after the 40 water circulates to the pipeline 27, and eventually in the upper water chamber 21, as there the hydrostatic pressure of the liquid gradually becomes less. Therefore, the dangerous steam spaces 45 cannot be formed in the tubes 20 and in the lower water chamber 22. The steam evolved collects in the evaporator 28, and it can be drawn from the arch 30 through a pipeline 32, which is governed by a valve 31.

An open cylindrical ash apron extension 33 50 is connected to the lower water chamber 22, which extension projects into the ash pan 34. The bottom of the ash pan 34 is provided with a travelling rim 35, which can be rotated on rollers 36. The outside of the ash pan 34 carries a 55 tooth-rim 37, into which grips a driving worm 38, by means of which the ash pan is rotated.

A conical grate 39 is arranged in the center of the ash pan. In the upper part 40 of the grate 39 there are provided the openings for admission 60 of air and steam from beneath the grate into the fuel bed on the grate. The ash pan 34 opens outwardly from the grate 39. Underneath the grate 39 the ash pan bottom is provided with a conical extension 41, which has its cylindrical 65 end 42 dipping into a sealing cup 43, which is filled with water or another suitable liquid. The pipeline 44 is in connection with the casing of the sealing cup 43. Air and water-steam are blown through the pipeline 44 underneath the 70 grate 39. It is advisable to use the steam which has been generated in the vessel 28 as water steam.

The steam-air mixture enters the gas producer fuel through the openings which are arranged in 75

the upper conical part 40 of the grate 39. The gas which is produced by the reaction between air and water-steam and carbon of the fuel bed rises upwards through the gasification chamber 1 of the gas producer. As the gasification chamber 1 is completely filled with fuel, also at its upper end, the gas is uniformly distributed essentially over the whole section of the gas producer. In this way uniformly distributed, the 10 gas then reaches the distillation chamber 2. Here the heat of the gas is transferred onto the fuel, bituminous coal. The coal is heated and the bituminous constituents will escape in the form of gases and vapors. The mixture resulting 15 from the producer gas or water gas and distilling gas is finally discharged through the pipelines 16 at the upper end of the distillation chamber 2.

The tubes 28 of the gas producer are suitably interconnected in a gas-tight manner. According 20 to Fig. 3, a metallic strip 46 is inserted between each two adjacent tubes 45, which for example correspond to the tubes 28 of the gas-producer according to Fig. 1. This metallic strip 46 extends transversally to the dash-dotted 25 connecting line 47, between the centers of two adjacent tubes 45. The metallic strip 46 reaches over the entire height or length of the tubes 45. This strip is slightly bent in the form of an S so that on one hand it fits well against the tubes 30 45 and on the other hand any undesired spaces between the metallic strip 46 and the tubes 45 are avoided. According to Fig. 4 the metallic strip 46a is flat. With this construction there are formed spaces between the ends of the strip 35 46 and the tubes 25a at point 48. These spaces 48 are not always desired, and especially not desired in those instances where as here the construction is to constitute the enclosure of a gas producer, as it would be easily possible that gas 40 streams may be produced in spaces 48 which give cause to the objectionable so-called "edge fire".

The metallic strips 46, 46a are connected at their opposite longitudinal edges to the tubes 45 by means of welding joints 49, 49a, preferably 45 made by electric welding. By this connection, strips 46 are elastic, accommodate the expansion of the tubes 45 when they expand upon being heated under service conditions. Even with expansion due to heat, the walls of the tube will remain always gas-tight when constructed according to my invention. This is of special importance, if the fuel lies on one side of the tube wall and hot gases are led along the other side 50 of the tube wall, for instance through the space 55 between the shell 23 and the tubes 28, according to Fig. 1, for the purpose of utilizing the heat of the gases for the generation of steam.

The construction of Fig. 4 in which the seams 60 49a are preferably made by electric welding is used for the heating-walls of steam boilers or for tube-walls which enclose the combustion or reaction chambers. The connecting construction according to Fig. 4 has advantages similar to 65 the construction according to Fig. 3, with reference to the flexibility and the gas-tightness.

It is of course understood, that there are still other possibilities for carrying out my invention according to Figs. 3 and 4 and it is not intended 70 to limit the invention in all its aspects to the methods of execution or the application of the tubular steam boilers, as described and shown.

The invention may also be applied to other technical contrivances, such as to cooling devices or to the protection of iron parts in chambers subjected to high temperatures.

In the mode of carrying out my invention according to Figs. 5 and 6, the tubes 51 corresponding to the tubes 28 of the gas producer of Fig. 1 are interconnected in a gas-tight way by the metallic strips 52, which run in direction essentially parallel to the connecting line 53, which is drawn through the center of the tubes 51. The connecting strips 52 are connected at the ends in a gas-tight way with the tubes 51 by means of welding seams 55, the connecting strips 52 extend over the entire height or length of the tubes 51. When using the strips within a gas producer, according to Fig. 1, the connecting strips 52 as well as also the connecting strips 46, 46a of Figs. 3 and 4 are welded above and below to the water chambers 21 and 22.

The space between the preferably bent strips 52 and the tubes 51 is filled with a refractory mass 54, a mass consisting of a mixture of ground coke, chamotte and a suitable binder, water-glass. By means of the mass 54 the connecting strips 52 are protected against the heat radiation from the one side of the tube wall.

Figs. 5 and 6 show the preferred form of tube connection of the invention for those tubes which lie closely together at one end and which show a certain greater distance at the other end, for instance for the tube wall which forms the conical gasification chamber 1 of the gas producer shown in Fig. 1.

The bent shape of the connecting strips 52 permits a relative movement of the tubes 51 against one another under expansion, but the gas-tight connection of the tubes is not disturbed.

I have above described my present invention on the lines of a preferred embodiment thereof, but my invention is not to be limited in all its aspects to the mode of carrying out as described and shown since the invention may be variously embodied within the scope of the following claim.

I claim:

A gas producer comprising a shaft for the fuel to be gasified, the inner face of at least the gasification zone of the shaft being constituted of a number of generally vertical tubes with the tubes unprotected from surface contact with fuel in the gasification zone, the tubes being connected each at their upper and lower ends with annular water chambers provided with means for supply of a cooling liquid into the water chamber for the tubes, said tubes being interconnected with each other to form a gas-tight wall by metallic strips accommodating expansion of the tubes, said strips being coextensive in length with the tubes and nesting between two adjacent tubes so as to be generally parallel with a line connecting the tube centers, each of said strips having its longitudinal edges welded to the tubes between which they nest on one and the same side of the center line of the tubes and having the portion between said longitudinal edges curved oppositely to the curvature of the portions of the tubes that are on the same side of the line connecting the centers of the tubes that the welds are on, the space between each strip and the adjacent tubes they respectively connect being filled with a mass of refractory material.

HEINRICH KOPPERS.
